KEY CONTROLLED MACHINES WITH RECORD PUNCHING AND PRINTING MEANS

Ralph E. Page and Stanley J. Culveyhouse,
Poughkeepsie, N. Y., assignors to International
Business Machines Corporation, New York,
N. Y., a corporation of New York

Application July 22, 1947, Serial No. 762,562

13 Claims. (Cl. 164—113)

1

This invention relates to record punching machines and more particularly to the type which is controlled by a keyboard to provide a sequentially punched and printed record, preferably in the form of a tape, of data pertaining to successive transactions entered in the machine.

The main object of the invention is to devise a record punching machine of the above described type which will not only provide said printed and punched tape record but also provide for issuing a printed check for certain kinds of transactions and provide for the printing upon a sales slip the data for certain other kinds of transaction.

A still further object of the invention especially related to the punching mechanism is the provision of means to effect the perforating of a separate record of each desired transaction which comprises a tabulating card which may be separately used for statistical purposes.

Machines of this general type have previously been designed and as is well known may comprise a cash register, a group of which may be used in each store, one for each or several departments and each controlled by a number of clerks or cashiers. Each register provides its own punched tape record of the transactions entered therein. Where the store is one of a series in a chain, there will be provided many of these punched record tapes which are sent to a central auditing office for auditing purposes.

The perforated tapes contain not only the amount of the sales but other classification data relating to the sales, such as merchandise number, cashiers, clerks or department numbers, serial number, date, etc. By such designations a segregation of sales according to different classifications may be obtained with the use of an auditing machine of which many have been devised, such as the tape controlled auditing machine in the patent to M. Goldberg, No. 1,694,009. The auditing machine produces a summary record of sales pertaining to different classifications so that at the termination of a particular period a classified summary of sales of all stores in a chain can be provided.

As previously mentioned, the present machine has for one object the punching and printing of a tabulating card, particularly used in connection with charge transactions, although not confined to such special use. Certain punched classification data thereon, such as department number, merchandise number, clerk or department number, kind of transaction, serial number, total of each sale, etc., enables such cards to be used in commercially available tabulating and

2

sorting machines to augment the provision of summary records, and enables further segregation and securing statistics by such commercially available sorting and tabulating machines. Such tabulating cards may be used in connection with sorting and tabulating machines in the store itself, this feature enabling a cash register system to be readily incorporated in well known tabulating systems for accounting and billing purposes to take care of charge transactions.

A still further object of the invention is to devise the machine so that two forms of sales may be handled, one comprising a sale of a single item, and the other multiple items only the total of which should appear on the issued check, perforated record, or inserted sales slip, but each item of such multiple items should be recorded upon the printed and punched tape.

More specifically it is an object of the invention to cause recording upon an inserted sales slip, or issued check of only the total of multiple items, entering in the transaction, or a single item on the inserted sales slip or issued check.

A still further object of the invention is to devise a single punching mechanism which will concomitantly punch the record tape and the tabulating card which is inserted in the punching machine in overlapping relationship with respect to the tape. An extended feature also consists of printing upon such tape the amount of each item or total, thus interpreting the punched data.

Another feature of the invention related to the punching mechanism is to provide for the punching of the tape in a combinational hole arrangement, as contrasted with the well known Hollerith numerical code, and thereby conserve space on the tape.

A still further object of the invention is to devise a punching mechanism wherein different combinations of punches are selected, but the punching is effected index point by index point.

Another object of the invention is to devise a punching mechanism which includes a single punch pin which is selectively activated at successive index point positions to effect combinational hole punching.

Another object of the invention is to devise a serial number punching mechanism to punch serial numbers consecutively and in a combinational hole arrangement.

A still further object of the invention is to apportion a part of the punching mechanism for punching representations of department and clerks numbers, and to provide a department and

clerks number set up device in the form of rotatable drums carrying number setup control members, thereby setting up a large number of designations in a convenient way.

A still further object is to provide said number setup control members in the nature of identification slugs insertible in the machine so that the machine may be used in any department, and different clerks may insert their identification slugs in any machine in any department.

Another object of the invention relates to the provision of interlocks of a variety which, in general, insures that desired data will be recorded by requiring the depressions of keys in certain banks and the setting up of clerks and department numbers.

A still further object of the invention is to simplify the printing mechanism by the provision of a single set of printing wheels adapted to be shifted for coordination with a plurality of platens to print data upon two places on an inserted sales slip, or once upon an issued check, and also upon the tape and record card to be punched.

A still further object of the invention principally concerned with the printing mechanism is to devise means to condition the printing mechanism so that each of the multiple items will not be recorded on an issued check, but upon entering a single item of a sale or a total of multiple items the printing mechanism will be conditioned by a total key to either print the total of multiple items or a single item on an issued check, or print on an inserted sales slip when such is inserted within the machine.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the machine showing particularly the banks of keys in the keyboard arrangement, the item and total motor bar bank, and the clerk and department number setup devices.

Fig. 2 is a transverse sectional view taken on the line 2—2 of Fig. 1.

Fig. 2a is a detail view of part of the key interlock mechanism.

Fig. 3 is a transverse sectional view taken on the irregular section line 3—3 of Fig. 1.

Fig. 4 is a transverse right hand end view of the machine with the cabinet removed and is taken on the line 4—4 of Fig. 1.

Fig. 4a is a detail of the key releasing mechanism for certain banks which is operative upon taking a total.

Fig. 5 is a front elevational view of the department and clerk number setup device.

Fig. 6 is an end view of one of the insertible department or clerk number representing slugs.

Fig. 7 is a view in side elevation of one of the said slugs.

Figs. 8, 9 and 10, when assembled in the named order, is a side spacing diagram of the machine showing the cooperative relationship between interrelated parts.

Fig. 11 is an enlarged sectional view of the rear end of the machine showing particularly the tape and perforated record punch mechanism for punching combinational holes.

Fig. 12 is a sectional view taken on the irregular section line of Fig. 11.

Fig. 13 is a representation of an issued printed

check for a sale which is also recorded on the tape.

Fig. 14 is a representation of a sales slip made out by the clerk pertaining to multiple items which are recorded on the tape, and also representing at the lower and central portion thereof the total and classification data of such sales recorded by the machine in a total operation.

Fig. 15 is a representation of a portion of a perforated record tape indicating thereon two multiple items pertaining to the sales slip in Fig. 14 and the accompanying perforated total of such multiple items effected in a total operation. The tape also has recorded thereon a single item sale for which the check in Fig. 13 is issued.

Fig. 16 is a representation of a portion of a tabulating record card written on by the clerk through carbon paper at the time the sales slip in Fig. 14 is made out and also showing how perforations are made to represent the totals and other classification data pertaining to the total of the multiple items.

Fig. 17 is a representation of the code utilized to represent numerals.

Fig. 18 is a timing chart of the machine.

Fig. 19 is a view in side elevation showing the main operating clutch and associated release mechanism.

Fig. 20 is a view taken on the line 20—20 of Fig. 19.

Figs. 21 and 22 are detail views showing the punch operating clutch and its engagement and disengagement control means.

Fig. 23 is a view in side elevation of the accumulator and its associated entry actuating segments.

Fig. 24 is a side elevational view showing the reciprocating mechanism for shifting the type wheel support frame to different recording positions.

Fig. 25 is a detail view showing the type wheel inking mechanism.

Fig. 26 is a view of the type wheel support frame showing the assembly of type wheels.

Figs. 27a, 27b, 27c are successive position views of the platen operating means.

Fig. 28 is a view in side elevation of the machine number slide setting means.

Fig. 29 is a view in side elevation of the date setting means for the related date number slides.

Fig. 30 is a detail view showing the serial number punching device.

Fig. 31 is a wiring diagram of the electrical circuits.

Fig. 32 is a side elevational view of the platen printing control mechanism for the check and sales slip printing mechanism.

Fig. 33 is a side elevational view of the check and sales slip printing mechanism which is on the opposite side of Fig. 32.

Fig. 34 is a plan view of the check and sales slip printing mechanism.

Fig. 35 is a plan view of the tabulating record card guide and support plate.

Fig. 36 is a sectional view taken on the line 36—36 of Fig. 35.

Fig. 37 is a plan view of the sales slip carriage.

Fig. 38 is a sectional view taken on the line 38—38 of Fig. 37.

Keyboard

Fig. 1 shows the arrangement of the keyboard which comprises thirteen banks of keys and also a motor operating bar 10 designated Item, which is operated for each item of a multiple item sale,

and a supplemental motor operating bar 11 designated Total, which is operated after the multiple items have been entered to punch a total of the items on the card and the tape and print such total on either an inserted slip or issued check. This Total is also used in the same manner when the transaction is a single item. The banks of keys include two cashiers' keys 12 and 13 marked A and B, which are used when the machine is cashier operated. Five banks of keys 14 are for recording coded numbers representing the type of merchandise, and five banks of keys 15 are for recording the amount of the sale. The bank of transaction keys 16 are for recording the type of transaction, and two keys 17 and 18 in a single bank represent Tax and No tax for designating by recording whether the sale is taxable or not. As shown in Fig. 5, there is a drum 19 manually positionable for representing the department number in which the sale is made and a supplemental drum 20 manually positionable for representing the number of the clerk handling the transaction.

Keyboard construction

The keyboard construction is substantially alike for each of the banks of keys and is shown in Figs. 2 and 6. A pair of cross bars 25 carry for each bank a U-shaped member having lateral portions 27, 27a in which are slidably mounted the key stems. A cover plate 26 over the key banks also guides the keys. There is also provided the usual slidably mounted spring operated key detent plate 28. The key stems 29 carry at their tops key caps 30, and each of said keys is depressible against the action of a spring 31. In the customary manner, a beveled edge 32 of each key stem operates in a related slot (not shown) in the detent plate 28 upon depression of said key to move said detent plate 28 forwardly or to the left, as shown in Fig. 2, until a shoulder 33 of said key is beneath the slot in said detent plate 28. A spring 34 is now effective to retract the detent plate 28 rearwardly or to the right, as viewed in Fig. 2, thereby latching the depressed key downward. The keyboard is of the "flexible" type, enabling correction or release of any depressed key by operating another key. If a key is not released by the operating mechanism, it will stay depressed as will be evident later.

Pivoted at 24 on each key frame is a triple arm member comprising arms 35, 36 and 37, said arm 35 projecting in a slot in the detent plate 28 so as to rock the triple arm 35, 36, 37 counterclockwise by the detent plate 28, when a key in each bank is depressed. Arm 37 is a stop arm related to the differential mechanism to unlock the latter for differential movement in a manner to be subsequently described. Arm 36 is provided with a shouldered notch 38 (Fig. 2) cooperating with an arm 39 attached to a shaft 40. The parts 38, 39, 40 are related to an interlocking mechanism now to be described and there is a lock arm 39 for the cashier's bank of keys, the merchandise number bank of keys, the transaction bank, and the tax bank of keys (see Fig. 8).

Item and total motor bar bank

The item motor bar 10 and total motor bar 11 are specially constructed and each consists of a stem 29a secured to the upper manually operated bar portion and guided in the key frame, but are not latched down by the detent 28. The other stem 29b is similarly guided but is latched down by the detent 28 and is not attached to the man-

ual bar portion. Stem 29b is pushed down by said bar to function as a differential stop in this bank. The function of stems 29a will be explained later.

Interlock mechanism

The mechanical interlock mechanism is provided so as to prevent the normal operation of the Item motor operating bar 10 or total motor bar 11, until either an A or B cashier's key, a merchandise number key, a transaction key and either a Tax or No tax key are depressed. In the case of a total operation after a series of items have been entered, the 1 key in the units order of the merchandise key bank is depressed to release the interlock. As shown in Fig. 15, 00001 will be printed, but this is meaningless.

Referring to Fig. 4, it will be seen that the Item motor operating bar 10 or Total bar 11 operates upon a detent plate 28 in the manner previously described, so that depression of either of these bars will move detent plate 28 forwardly. Said detent plate has an operative connection to a special triple arm comprising arms 45, 46 and 47, the arm 47 curves upwardly and carries a pin 48 fitting in an open slot of an arm 49 secured to the shaft 40. Referring to Fig. 8, it will be seen that the shaft 40 carries three arms 39 which are so spaced that one of them cooperates with the arm 36 of the cashier's bank of keys, one with the arm 36 of the transaction key bank, and one with the arm 36 of the Tax and No tax key bank. If an attempt is made to depress the Item bar 10 or Total bar 11 before a key in each of these banks is depressed, movement of detent plate 28 (Fig. 4) forwardly will rock the triple arm 45, 46, 47 counterclockwise and through the connection of arm 47 with the arm 49 shaft 40 will be rocked counterclockwise (Fig. 2). Hence, if one of the cooperating triple arms 35, 36, 37 has not been rocked counterclockwise (Fig. 2) and is held in rocked position by the failure to effect a depression of key in each of the aforesaid banks, arm 39 will project against the shoulder 38 of one of the unmoved arms 36 to prevent depression of the Item bar 10 or Total bar 11. If a key in each of the aforesaid banks has been depressed, shaft 40 will be free to be rocked, and as a result of the depression of the Item bar 10 or Total bar 11 the machine will then go into operation.

For providing an interlock from the merchandise number key bank, there is provided a bail comprising arms 62, 63 between which there is extended a rod 64. A spring 65 between rods 64 and 53 urges rod 64 to rest on the rod 53, as seen in Fig. 2. The arm 63 has a locking shoulder like shoulder 38, and therefore unless the bail 62, 63, 64 is rocked by the depression of a key in the merchandise number key bank, the arm 39 cooperating with arm 63 will not be unlocked. Hence, a key in this bank must also be depressed.

There is also an electrical interlock mechanism which will prevent the depression of the item motor bar 10 or total motor bar 11 until certain conditions are established, as will be described.

Merchandise number and amount key release mechanisms

Means is provided to release the depressed keys of the merchandise number and amount banks at the end of each item or total operation or in others after each operation of the machine whether for an item or total. To this end there is secured to a rock shaft 50 (Figs. 2, 4 and 8) a bail which comprises arms 51 and 52 carrying a

cross rod 53. Bail rod 53 is wide enough to cooperate with the arms 36 of the triple arms 35, 36, 37 associated with the merchandise number key banks and the amount key banks. The elevation of said rod as viewed in Fig. 2 by means to be described will engage the arms 36 in the key banks, which have been rocked by the depression of a key in that bank and to such an extent that detent plate 28 is shifted forwardly to unlatch the depressed key.

For the purpose of rocking shaft 50 to release the aforesaid depressed keys, there is a connection to the machine operating mechanism as follows: Secured to the shaft 50 is an arm 57 (Figs. 4 and 8) which has a link connection 58 to a bell crank 59 and one arm of the latter is in operative association with a stud 60 carried by a gear 438 driven in a manner to be subsequently described. Stud 60 engages one arm of the bell crank 59 and rocks the latter to depress the link 58 and through arm 57 rocks shaft 50 counterclockwise to release the depressed keys.

Key release for cashier's keys

It is preferable to have the depressed cashier's keys remain depressed for a series of item entering and totaling operations, and, therefore, there is no connection from the operating mechanism to release these keys. By virtue of the "flexible" keyboard construction a depressed cashier's key can be released by simply depressing the other cashier's key either partially or fully, if it should remain depressed.

Release of item and total motor bar bank and keys of transaction and tax and no tax key banks

It is desirable that the key stops and depressed keys of the transaction and tax and no tax key banks be kept depressed during a series of multiple item entering operations and released only at the end of a total recording operation.

Numerical 110 (Fig. 4) represents a stepped plate of the differential mechanism of said item and total motor bar bank which moves one step for an item operation and four steps for a total operation by reason of cooperation with latched down key stems 29b. In the four-step movement, a projection 41 will engage a stud 42 of an arm 43 pivoted by a stud 44 and rock said arm 43 until the projection 41 passes by the stud 42, a spring 54 connected to a stud 55 on said arm then urging the arm to normal.

Loosely mounted on the rod 50 is a sleeve 66 (Fig. 8) to which arms 67, 68 are connected, said arms carrying a bail rod 69 under the arms 36 related to the Tax-No-tax, Transaction key banks and arm 46 of the motor and item bar key bank. Bail rod 69 is urged by a spring 70 to effect this relationship. The depressed keys in the Tax-No-tax, transaction and latched down key stems 29b of the motor and item bar banks are released by the elevation of the bail rod 69 effected by the following described means.

When the projection 41 returns, it will reversely rock arm 43 counterclockwise and spring stud 55 coacting with the side arm 68 will elevate said bail rod 69.

Clerk and department setup devices

Means is provided in the machine for setting up a representation of the number of the clerk operating the machine as well as a representation of the number of the department in which the sale was made. The description will be given

in connection with Figs. 1, 2, 3, 5, 6 and 7. The construction of the department and clerk number setup drums 19 and 20 is alike, and it will be described with reference to one only.

The clerk setup device consists of a cylinder 75 provided with a series of twenty slots 76. For setting up the department representation only, six slots are provided in the same form of cylinder. Insertible in these slots are slugs 77 or recording control members, one of which is shown in detail in Figs. 6 and 7. These slugs fit completely in the slots and, when inserted, complete the periphery of the drum at that place.

For the purpose of exteriorly setting up the particular department or clerk designation for recording purposes, to the cylinder 75 there is secured a pinion 78 (Fig. 5) meshing with a rack 79 which is slidably mounted on a fixed rail 80. The rack 79 has a finger piece 81 which is slideable along a chart 82 (Fig. 1) which is marked with the letters or names indicating the various clerks. In the same way for rotating the department cylinder, there is provided a pinion 83 which meshes with rack teeth of a rack slide 84 slideable on the rail 80, said slide also having a finger piece 85 (Fig. 1) which acts as a pointer passing alongside of an indicating chart 86 designated with letters or names representing the different departments.

In some machines all of the clerk or department setup positions will not be utilized which will be indicated by the absence of a slug 77 in such positions and to prevent the operation of the machine, unless the drums are set up to recording control positions corresponding to inserted slugs 77 in either cylinder, and an electrical control described hereinafter is provided.

Bearing against the periphery of both cylinders 75 at the forward end there is provided a plurality of arms 87 (Fig. 5) which have depending integral arms 88 interconnected by a spring 89, so that their upper wedge-shaped ends coact with the periphery of the cylinders to sense whether there is an inserted slug 77 in recording control positions in both cylinders. When said arms 87 are in the position shown in Fig. 5, due to the insertion of slugs 77 in both cylinders at the recording control position contacts 90 and 91 will be closed. However, in the absence of a slug at the recording control position in either cylinder, spring 89 will rock either arm 88 away from contacts 90 or 91, so as to enable the opening of contacts 90 or 91 by their own resiliency.

Another set of sensing devices similar to that just described are positioned further rearwardly to coact with the slots, which is permitted at this position by a reduced part 93 (Fig. 7) of the slugs 77, and the lower arms of such sensing arms 94 and interconnected spring 95 are shown in Fig. 5. The controlling contacts 96 and 97 are shown in Fig. 31. Thus, unless the drum is at an exact sensing position either arm will be rocked to open either contacts 96 and 97.

Opening of contacts 90, 91, 96, 97 will be described in connection with the wiring diagram to show how their opening prevents the operation of the machine.

As will be subsequently described, the slugs 77 inserted in the setup drums 19 and 20 control the position of punch and type wheel recording elements, so that there will be recorded by punching and printing a designation of the department, as well as the clerk making the sale.

From Figs. 6 and 7, it will be seen that each slug 77 is made of two parts 77a, 77b, and is hollow

within to receive a plurality of pins 98 which are of differential lengths. The two-part slug 77 is fastened together by any suitable manner to hold the pins 98 against movement. As will be later described, sensing pins project against the pins 98 and in accordance with their lengths set up type wheels and punch slides to record a number corresponding to the clerk or department designation.

Referring to Fig. 5, it will be seen that the cylinders 75 are pivotally mounted on their respective fixed supporting shafts 100 and fixed to each shaft 100 is a plate 101 which has a cutout portion 107. A headed screw 103 maintains the concentric plate 101 in fixed position and also a plate 102 which is loosely pivoted on said screw stud. A spring 103 is stretched between a stud 104 carried by the plate 102 and a stud 105 secured to the concentric plate 101. Hence, irrespective of the rotation of either cylinder the plate 101 in cooperation with the ends of the slugs 77, which have been inserted, will maintain these slugs in inserted position to prevent their accidental movement. For the particular slug 77, which is in sensing position, the extremity of the plate 102 will cooperate with the end of such slug and prevent its outward movement when the numeral indicating pins 98 carried thereby are sensed for recording control, as will be subsequently described.

In order to enable the removal of a slug 77 or the insertion of one at a desired position, the plate 102 is merely rotated a slight amount by a knob 106, so that the slug 77 may be withdrawn through the cutout portion 107. Of course, when a slug is to be inserted a similar movement of the plate 102 is effected by knob 106, so as to entirely expose the slot in which the slug is to be inserted.

Differential mechanism

The differential mechanism will be described with particular reference to Figs. 2 and 8. In view of the substantially similar construction of the differential mechanism for each key bank, it will be described for one order only. The differential mechanism for each key bank comprises an actuating rack 110, a stepped stop plate 111, and an aligning plate 112, these being adjacently mounted as shown in Fig. 8 for each of the various key banks. The stepped plate 111 is slidably mounted on the plate 110 by three pin and slot connections 113, and pivoted on a stud 114 carried by the plate 110 is a clutch pawl 115 which has a pin and slot connection 116 with the stepped stop plate 111. A spring 117 is interposed between plates 110 and 111 in such manner that the resiliency of the spring 117 urges plate 111 to be moved forwardly with respect to plate 110, so that by the pin and slot connection 116 pawl 115 is rocked downwardly, so that a shouldered portion 118 is normally in engagement with a universal operating bar or plate 119. The plate 119, as will be described, is given a constant excursion for each operation of the machine to thus effect a differential forward movement of the actuating plate 110 to a distance commensurate with the key depressed, the differential stopping being effected by virtue of the engagement of the lower portion of the key stems 29 or 29b (Fig. 4) with the stepped shoulders 120 of the plate 111. The steps 120 are identified by digits 1-9 which indicate the steps of movement effected by the differential mechanism, depending upon the key depressed. For example, when the lowermost key in a bank is depressed, which is the 1 digit key,

the stepped plate 111 will be moved forwardly one step until it strikes the depressed key. When the 2 digit key is depressed, the step 120 marked "2" will determine the two steps of movement of the plate 111, etc. However, when no key in a bank is depressed, the previously mentioned arm 37 will be in coaction with an edge 121 of the rear portion of the plate 110 and, as will be described, this will prevent any movement of the actuating plate 110. Plates 110 and 111 are slidably mounted on a fixed rod 123 which cooperates with an elongated slot 124 in the plate 110 and also on a rod 122 in engagement with slots 125 formed in both the plates 110 and 111.

When a key in a bank is depressed, the universal bar 119 will move forwardly and rearwardly by a cyclic operation of the machine by means to be subsequently described and, if a triple arm 35, 36, 37 has been rocked, arm 37 will be moved away from the locking edge 121 of plate 111 in the same order. The forward portion of the universal bar 119 now coacting with the shoulder 118 of the latch pawl 115 will move plate 110 forwardly and with it the slidably mounted stepped plate 111, this movement continuing forwardly until a step 120 strikes the depressed key. The abutment of a key stem with a step 120 will cause a slight forward movement of the plate 110, thus rocking the latch pawl 115 so that a stud carried thereby will engage an aligning notch 128 of the aligning plate 112. Shoulder 118 is now above the universal bar 119 and the latter can be moved further forwardly to its complete extent, and by passing underneath the clutch pawl 115 it will hold the differential mechanism in stopped position. The aligning plate 112 is, as previously described, mounted adjacent the plane of the latch pawl 115 and is held in fixed position by fixed rods 122 and 123.

This forward movement of the differential mechanism is utilized to set type wheels and punching recording mechanism to digit representing positions and, after the recording and punching operations have been effected, the universal bar 119 is restored. In its restoring movement it will engage a shouldered portion 129 of the plate 110 and thereby restore all the parts of the differential mechanism to normal. At the final return step of movement of the differential mechanism, latch pawl 115 will again be rocked so that its shoulder 118 again passes over the forward edge of the universal bar 119, the parts now being shown as in Fig. 2.

For those key banks in which no key is depressed, it will be seen that the initial movement of the plate 111 will cause locking edge 121 to engage the arm 37, and the operative association of these parts is the same as performed by the abutment of a step 120 with a key stem. Thus, plate 111 will be immediately shifted and rock latch pawl 115 directly out of engagement with the universal bar 119. No differential movement will be given to the parts 110 and 111, and the universal bar 119 will, in this case, be moved forwardly its complete extent and rearwardly without effecting any movement of such parts.

The means to effect an invariable excursion of plate 119 is as follows:

Four rack plates 130 (Fig. 8) similar to plate 110 but having no attached parts are connected by screws 131 (Fig. 2) to the plate 119 and, therefore, plate 119 is slidably mounted on rods 122 and 123. Each of the plates 130 meshes with a related gear 132 (Figs. 4 and 8) attached to shaft 142. Attached to shaft 142 is a gear segment 133.

Meshing with the gear segment 133 is a segment 134 (Fig. 4) which is part of a cam follower arm pivoted at 135 and having rollers 136 cooperating with complementary cams secured to a cam drive shaft 271. Said cams by one revolution of shaft 271 effect a reciprocation of universal plate 119 by the above described operating mechanism.

Cross over connections from the differential mechanism

There is preferably incorporated in the machine a punching and printing mechanism which punches and prints, on a tape contained in the machine, data pertaining to a transaction and also punches and prints upon a card which is inserted for cooperation with the punching mechanism.

It is evident that in view of the required narrow spacing of the punching slides to be subsequently described to punch a form of card to be identified and the grouping of the type carriers to print close together, and the fact that the banks of keys are widely spaced as shown in Fig. 1, and the other sources of data setups are in different places in the machine, crossover mechanism must be provided to cause the differential setting from the various sources to be imparted to the punch slides and printing wheels, which are separate but closely grouped together. The preferred form of crossover connection for effecting this result will now be described.

Referring to Figs. 2, 3 and 8, there is loosely mounted upon a shaft 142 a series of gears 143 and for setting punch slides 144 (see Fig. 3) certain of said gears 143 mesh with rack teeth 145 formed at the upper part of said slides. Certain of the gears 143 are rotated directly by the slides 110 of the differential mechanism controlled by all the key banks or other setup devices, and to cause the rotation of a particular gear 143 which meshes with the corresponding punch slide 144 there is provided crossover connections which are well known in the art.

Referring to Figs. 2 and 3, there are shown a series of shafts 146 and another series of shafts 147. In general, a connection is made from a gear 143 which is moved by a setup device or differential mechanism by having said gear 143 mesh with a pinion 148 which is connected to a sleeve 149. At the other end of said sleeve there is a similar pinion which directly meshes with the gear 143 which meshes with the punch slide 144. In this manner, irrespective of the position of a gear 143 to which a differential movement is given, either by the differential mechanism or a setup device, movement is communicated to the corresponding gear 143 which sets the punch slide 144.

In view of the fact that such crossover connections are well known in the art, it is thought unnecessary to describe each manner of connecting parts together for simultaneous movement to set the punch slides 144 to differential positions.

Figs. 8 and 9 disclose the arrangement of crossover shafts, the gears 148 and sleeves 149 raised thereto to set all of the punch slides 144.

Setup of punch slides by clerks and department setup devices

Three of the punch slides 144 are set to punch a digit representation of a number representing the department, and four of such slides are set up to represent the number of the clerk.

To accomplish this, there are slidably mounted on the rods 122 and 123 three slides 155 (Fig. 3)

which set up punch slides 144 through intermediate gears 143. Each of these slides has attached thereto a sensing pin 156 which moves forwardly to cooperate with a related pin 98 of the slug 11 in the cylinder of the department setup device, which is in recording control position. The group of slides 155 are normally retracted by the universal plate 119 and, as the latter moves forwardly, springs 157 urge the slide 155 and sensing pin 156 forwardly to effect the coaction with the related pin 98. In this manner the group of slides 155 set related punch slides 144 differentially to represent the department number.

The slug 11 which is in the cylinder of the clerk's setup device and in recording control position is sensed in a similar manner and to effect the positioning of the corresponding punch slides 144 there is provided a group of four slides designated 158 in Fig. 8.

Alignment of punch slides

It is necessary to align the punch slides 144 so as to insure that punched holes are made at the exact index point positions, and the mechanism for performing this is best shown in Figs. 2 and 11.

The rack slides 144 are provided with aligning teeth 160 which are at the underside of each slide. Extending across the slides is an aligning bar 161 which is carried by a plurality of arms 162 attached to a rock shaft 163. The rock shaft 163 has secured to it an arm carrying a roller 164 overlying the rear arm 165 of a double arm, the forward arm of which bears against an operating cam 166 secured to a drive shaft 277.

After the slides are in differentially set positions at about 60° of the cycle (see Fig. 18), cam 166 rocks the double arm and through arm 165 rocks the shaft 163 so that aligning bar 161 fits in the tooth spaces of the slides to align them and hold them aligned during the punching operations. After the punch operation is completed at about 270°, the cam allows the aligning bar 162 to descend and thus release the punch slides 144 for return to home or normal positions. The timing diagram of Fig. 18.

Punching mechanism

The punching mechanism is devised to punch a tape and card according to the column spacing of the well known 80-column card, shown in the Lake Patent No. 1,772,492, but the numerical data is punched according to the code shown in Fig. 17, so as to conserve record space.

Each punch slide 144 carries an isolated punch interposer 170 and a group of five punch interposers 171, four of which have pointed ends 172 (see Figs. 3 and 11). Each interposer carries a stud 173 which rests upon a rail 174 carried by a reciprocating punch frame. The punch interposer 170 is confined by four studs 175 carried by the punch slide 144 and the group of five interposers are similarly confined by four studs 176, and by means of which the interposers 170, 171 may individually slide vertically on the punch slide 144.

The punch slide 144 is moved rearwardly 1-9 units, according to the digit setup 1-9, and in the 0 or unmoved position of the slide interposer 170 causes punching of a single hole at the 0 index point position effected by a projection 177 of a punch bar 178. As the interposer 170 moves to the right for digit positions 1, 2, 3, 4, it will operate with projections 177₁, 177₂, 177₃, 177₄ of

punch bar 178 to punch holes at index point positions 1, 2, 3, 4, according to the code of Fig. 17.

At digit position 5 of punch slide 144, interposer 170 is now out of cooperation with punch bar 178 but the right hand interposer of group 171 is now beneath punch projection 177, but in such position with respect to a punch pin 179 that the latter will punch a hole at the X index point position. Thereafter, for digit positions 6, 7, 8, 9 the right hand interposer of group 171 will cooperate with punch bar projections 177₀, 177₁, 177₂, 177₃ to punch a hole at the 0, 1, 2 and 3 index point positions. However, at such digit positions 6, 7, 8 and 9, one of the interposers of group 171 having the pointed end will be beneath the punch bar projection 177₀ and in such position with respect to the punch pin 179 that a hole will also be punched at the X index point position for digit positions 6, 7, 8 and 9, as will be evident from the code in Fig. 17. As this group moves to the right for digit positions 6, 7, 8 and 9, the pointed ends of some interposers will cooperate with slots between the punch bar projections to prevent improper hole punching. Summarizing, the punch bar projections and interposers are so designed for cooperation that according to the digit positions 0-9 of a punch bar slide punching will be effected at index point positions, according to the code of Fig. 17.

As will be evident from the timing diagram, the punch slides 144 are advanced to digit position at 62°, after which time the punch pin 179 is moved to the left over the stationary card to be punched in succession over the index point positions in the order 4, 3, 2, 1, 0, X. When the punch pin is at such position and an interposer is over the punch pin 179 and beneath a punch bar projection, a hole is punched by the downward movement of punch bar 178. At each successive position of the punch pin 179, the punch bar 178 is reciprocated, as will be evident from the timing diagram.

The means to shift punch pin 179 successively to the left comprises a punch carrier unit having side frames 180, 181, (Fig. 11) connected together in spaced relation by end plates 182, 183 (Fig. 12). The frame 180—183 may be guided by having the plates 180, 181 move in tracks in the base plate to enable its position step by step.

A block 185 carried by the side frame 181 has a hole in which is fitted a plunger 186 having either of two positions maintained by a spring-pressed ball detent 187. A lower projection 188 of the plunger 186 cooperates with mutilated worm teeth 189 of a cylinder 190 secured to a drive shaft 191. As the cylinder rotates in the arrow direction, the angular teeth 189 will engage projection 188 and thus shift the frame one step to the left, after which a long dwell takes place, as is evident from the timing diagram. The worm wheel teeth 189 moves the frame six steps, and at the dwell position of the frame an aligning disk 192 carried by shaft 191 engages a tooth 193 of an aligning bar 194 carried by the frame plate 180 to hold the frame in shifted position while punching is being effected.

The configuration of the cam portion 190a effective at the last step is such as to elevate plunger 186 upwardly to prevent interference with the return of the frame. When the frame is returned to normal by means to be later described, a cam edge 195 of a fixed bar 196 depresses the plunger 186 to normal position in Fig. 11.

The frame carries a die plate 197 having a die hole for the plurality of punch pins 179, and over

said die plate the material to be punched is placed and underneath the series of punch pins 179.

Spaceably mounted from the die plate 197 to enable the insertion of record material to be punched and supported by said plate 197 is a longitudinal casting 200 in which the punch pins 179 are slidably mounted and held in slidable position by a mounting plate 201 attached to said casting 200.

The punch bar 178 is attached and carried by a pair of spaced plates 203, 204 which are cross-connected by cross bars 205 and a rod 206, thus providing a rigid frame carrying the punch bar 178. The aforementioned guide rails 174 extend between the bars 205 and are held in fixed position by assembly plates 207. For enabling the vertical reciprocating movement of said punch frame, the ends of rods 206 guide ears 208 (see Fig. 9) and extending portions 209 and 210 carried by side plates 203, 204, respectively, work in between spaced guide ears 211. Passing through a slot 215 (Fig. 11) in each of the side frames 203 and 204 is a drive shaft 216 carrying an eccentrically mounted punch operating cam 217 cooperating with the punch bar 178.

For each rotation of the shaft 216 and therefore cam 217, the punch frame is moved down and then up with the timing shown in the timing diagram, and to effect punching in each machine operation shaft 216 is given six revolutions to effect six reciprocations of the punch frame.

In accordance with the positions of the interposers 170 and 171, punch operating portions of punch bar 178 will through said interposers depress the punch pin 179 as the punch frame is moved downwardly to thereby project the lower portion of the punch pin 179 through the record material and into the die plate 197. The punching operations are successive since the punch pins 179 are moved step by step over the now fixed record material to punch at index point positions in the order 4, 3, 2, 1, 0, X, after which the punch pin carrying frame is returned to normal.

It is, of course, desirable that the depressed punch pins 179 be positively returned upward after each punching operation and without the expedient of a spring. To this end, each punch pin has a shouldered notch 220 and cooperating with said notches is a punch pin retracting bar 221 (Fig. 11). The punch retracting bar 221 is slidably mounted in the casting 200, and to enable downward movement of the retracting bar 221 coincident with the depressed punch pins 179 the bar 221 has secured thereto a pair of upwardly extending members 223, each of which has attached thereto a pin 224 working in a longitudinal slot 225 in each side frame 203, 204. Hence, punch retracting bar 221 is moved downwardly with the depression of the punch operating frame but may also move step by step to the left or return to the right with the corresponding movement of the casting 200.

For those punch pins 179 which have been depressed the elevation of the punch retracting bar 221 from its downward position will engage the upper shoulder of the notch 220 and positively return the depressed punch pins 179.

The punch chips pass through the die holes and into a chip receiving guide chute 227, which 70 receives the chips and guides them out exteriorly of the punching machine.

A card stop pin 228 is slidably mounted in the casting 200 and has attached thereto a pin 229 which has a connection to an operating lever 230, said lever being rocked to elevate the card stop

pin 228 when it is desired to insert a new supply of tape to be punched.

The card stop pin 228 enables the card to be inserted sufficiently to overlie the tape as shown in dotted lines in Fig. 15, so that part of the tape is printed by the printing wheels to represent the cashier, tax or no tax designation, the zeros of the merchandise number which is not set up for a total of multiple items, and "T" representing a total. The remaining imprint is on the card, as shown in Fig. 16. This partial insertion enables such data to be punched on the tape, but not on the card.

Main operating mechanism

The power for operating the machine is derived from a motor 240 (Figs. 4 and 8) which is set into operation when either the item or total motor bar is depressed. From the wiring diagram (Fig. 31) it will be evident that the circuit to motor 240 is normally open at contacts 241 and also contacts 610 to be later mentioned (see Figs. 19 and 20). Both the key stems 29a of the item and total bars 10 and 11 (Fig. 4) operate upon a slidably mounted pitman 242 normally urged upwardly by a spring 243, so that a T-shaped part 244 is under pins 245 carried by key stems 29a to cause said pitman to be moved downward when either motor bar is depressed.

Normally, the motor bars are locked against depression by an arm 246 which is urged by a spring 246a so that a hook 247 is in a shouldered notch in said pitman, so shaped that pitman 242 is locked against depression. When a solenoid 248 is energized in a manner to be explained, the arm 246 is rocked to unlocking position.

The lower end of said pitman 242 engages a wide stud 249 (Figs. 19 and 20) which is carried by a double arm 250 pivoted on a rod 251. After an initial rocking movement of arm 250 wide a stud 249 will engage an arm 252 which has a depending arm 253 arranged to close contacts 241 and thus set motor 240 into operation.

Arm 254 integral with arms 252, 253 has a hooked portion 255 overlying a spring-pressed pawl 256 pivoted on a now stationary disk 257. Said pawl 256 when released by the hook 255 rocks to pass in front of the hook and hold arms 252, 253, 254 rocked. Thus, an initial operation of the motor bars 10, 11 will close contacts 241 and pawl 256 will keep the contacts 241 closed to insure proper energization of the motor 240 which turns upon closure of contacts 241.

The armature shaft 258 of motor 240 carries a pinion 260 (Figs. 4, 8, 18) meshing with a gear 261 pivoted on a rod 262. Gear 261 has attached thereto a smaller gear 263 meshing with a larger gear 264 to which there is secured a shouldered clutch disk 265 loose on a shaft 266. A spring pressed clutch pawl 267 is pivoted on a cam disk 268 and is normally held in disengaged position by a clutch release arm 269. The motor is set into operation by closure of contacts 241 before clutch release arm 269 is rocked and, when a clutch engagement is effected, cam disk 268 and an attached gear 270 which are fast to said shaft 266 will be rotated.

To shaft 266 there is secured a worm wheel 275 (Figs. 4 and 10) meshing with a worm gear 276 (Fig. 9) secured to a cam drive shaft 277, and to this shaft the cam disk 278 on which the pawl 256 is pivoted is secured as well as a concentric disk 279 adjacent the cam disk 278. The disk 279 has a notch 280 in which the hook 255 normally fits as shown in Fig. 20. After a partial counter-

clockwise rotation of shaft 277 and after hook 255 leaves pawl 256, a concentric portion of disk 279 will engage the hook 255 and hold arm 252, 253, 254 rocked to keep contacts 241 closed. After one revolution of shaft 277, arm 254 is released to be urged by the resilient blade of contacts 241 to cause its hook 255 to re-engage notch 280 to lock shaft 277 at normal and prevent overthrow of parts beyond normal.

The double arm 250 carries a roller cooperating with the profile 281 of cam 278 which is of such cam formation that it will rock arm 250 counterclockwise and by stud 249 return pitman 242, and the stem 29a of the depressed item or total bar to normal to prevent a repeated operation of either motor bar and cause a misoperation of the machine.

The clutch release arm 269 goes back to clutch releasing position after twelve revolutions of shaft 266 have been executed, and due to the gear ratio between worm wheel 275 and worm gear 276 after one complete revolution of shaft 277.

Referring to Figs. 19 and 20, the arm 252 overlies a lateral extension 286 integral with the clutch release arm 269, and a spring 287 between a fixed stud 288 and a stud 290 carried by a depending extension 291 of clutch release arm 269 keeps the latter in clutch engaging position. Rocking of arm 252 rocks clutch release arm 269 to clutch pawl releasing position.

The arms 252, 253, 254 rock back to normal position when one revolution of shaft 277 or twelve revolutions of shaft 266 have been executed, thus enabling the clutch release arm 269 to now be in a position to engage clutch pawl 266 and disengage the clutch. The parts are now in the position shown in Figs. 19 and 20.

Referring to Figs. 19 and 20 pivoted on the stud 262 is a latch plate 292, and a spring 293 extended between the stud 290 and a stud 294 on plate 292 causes said stud 294 to engage the top edge of extension 286, to thus enable plate 292 to move with clutch release arm 269 as a unit.

It is desirable to centralize the shaft 266 as it coasts home and to this end there is pivoted on a stud 295 an arm 296 drawn by a spring 297, so that a roller on said arm engages a cam portion 298 of cam disk 268.

When arm 296 is rocked by cam portion 298 during the first revolution of cam 268, a lug 299 of said arm latches beneath the now rocked latch arm 292, thus holding roller on arm 296 out of position to be engaged by cam disk 268. Near the end of the twelfth revolution, arm 292 rocks to unlatching position with the clutch release arm 269 to thus enable the roller to engage the cam disk 268 and centralize shaft 266.

Referring to Figs. 10 and 19, the gear 270 drives a gear 306 through an idler gear 305 and gear 306 is secured to a drive shaft 307 to drive the punching mechanism through a punch operating clutch now to be described.

Punch operating clutch

Secured to shaft 307 (Figs. 21 and 22) is a clutch disk 308. Loose on shaft 307 is a plate 309 carrying a spring-urged clutch pawl 310 normally held in clutch releasing position by a clutch release arm 311.

Arm 311 is pivoted on a stud 312 and has a sleeve connection 313 to an arm 314. The latter is connected to a pitman 315 attached to a cam follower arm 316 cooperating with a cam 317 attached to drive shaft 277.

The cam formation is such that at about 88°

(see Fig. 18) arm 316 rocks clutch release arm 311 through the aforesaid connection and the clutch engages and remains engaged for six revolutions of the twelve revolutions of shaft 308, after which cam 317 effects the clutch disengagement.

Attached to arm 309 is a bevel gear 320 which meshes with a bevel gear 321 rotatable with a sleeved gear 322. The gear 322 meshes with a gear 324 secured to the punch operating shaft 216 through an idler gear 323. Through this gear drive train punch operating shaft 216 is rotated to reciprocate punch bar 178 six times.

Rotatable with bevel gear 320 is a gear 325 driving a gear 326 attached to shaft 191 through an idler gear 327. Thus, the clutch just described will also effect six revolutions of the worm wheel drive shaft 191.

Accumulator

It is desirable to enter in an accumulator the totals of multiple transactions, or the item of a single transaction, so that the totals of all sales of a day or other period are obtainable.

Referring to Figs. 8 and 23, five of the gears 143 which are differentially rotated under control of the five banks of amount keys 15 mesh with segments 330 rotatable upon a rod 331. Mounted adjacent the segment 330 of each of the five orders is an accumulator entry segment 332 also pivoted on rod 331, and segments 330, 332 have a pin and slot connection 333 which, as is well known, is for the purpose of enabling a one-step movement of segment 332 for units carry purposes.

The accumulator comprises a frame 335 secured to a rod 336 and normally urged by a spring 337, so that the accumulator entry pinions 338 tend to mesh with teeth of the segments 332. The accumulator frame 335 has a depending integral arm 339 engaged by a roller 340 of a cam follower arm 341 loose on a rod 342 and engaging a profile cam 343 secured to cam drive shaft 277.

At the initial counterclockwise rotation of cam 343, the projection 344 will drop off the high part of cam 343 and cam follower arm 341 rocks counterclockwise to enable the release of arm 339, so that the accumulator frame will drop the accumulator gears 338 into engagement segments 332. The latter will rotate the gears differentially as they are elevated, and at the end of their differential movements the gears 338 are disengaged and segments 330 and 332 return idly to normal positions.

For each of the multiple items the item motor bar 10 is depressed which results in rotating shaft 277 to attempt an accumulator entry, and to prevent an accumulator entry for such items the accumulator gears 338 are not meshed until the total motor bar 11 is operated.

To the rod 336 there is secured an arm 350 (Fig. 4) normally abutting an arm 351, which is pivoted at 352 and has an integral arm 353 carrying a stud underlying the depressible stem portion of the total motor bar 11. The normal relationship shown in Fig. 4 keeps the accumulator frame locked against any rocking movement until the total motor bar 11 is depressed which carries arm 351 away from lock arm 350.

To enable carries for each higher order, each lower order segment 332 has pivoted thereon by a stud 360 (Fig. 23) a spring-urged latch pawl 361 engaging an edge 363 of the related segment 330. When an accumulator wheel goes from 9-0, a high tooth of such wheel engages a tooth 364a of a lever 364 and rocks the latter. Lever 364

engages a stud 365 on pawl 361 of the next higher order and rocks said pawl 361 away from edge 363, so that a spring 366 will move higher order segment 332 one step, permitted by the pin and slot connection 333 to transfer a unit to the next higher order wheel.

All unlatched segments 332 used for carries are retracted to be relatched by pawls 361 by related arms 367 secured to a rock shaft 368 operated by a cam 374 secured to shaft 277 through a link connection 369, 370, 371. A spring 372 attached to an arm 373 secured to shaft 368 retracts these parts to their normal position.

Printing mechanism

The printing mechanism includes a group of type gear wheels 380 mounted on a shaft 381 (Fig. 3) and are carried by a reciprocable frame 382.

These type wheels are adapted to print the line of data on the tape, inserted card, inserted sales slip, or issued check, as shown in Figs. 13, 14, 15 and 16.

These type gear wheels are differentially rotated by the slides 144, some of which are differentially set under control of the keyboard, or others remain set up by other data setup sources.

In general, the first of such slides differentially turn the printing gear wheels 380 clockwise and, while they are being turned in such direction, they are rolled under the meshed gear slides 144 one complete revolution by shifting said frame 382 carrying the shaft 381 on which the type wheels are mounted to the right until said type gear wheels are over a printing platen 383, which is then actuated to print on the tape and inserted card (see Fig. 27a).

Shaft 381 and frame 382 now return to the left, reversely rolling the wheels 380 a complete revolution until the wheels are over a platen 384 (see Fig. 27b) which is now actuated to print on the lower part of the inserted slip, as seen in Fig. 13. The shaft 381 and frame 382 are now shifted still further to the left, causing the rolling of the differentially rotated type gear wheels 380 until said wheels are over a platen 385 (see Fig. 27c) which is now actuated to print the line of data at the mid-portion of the inserted sales slip or on the issued check, as shown in Fig. 13. Thereafter, shaft 380 is moved to the normal position shown in Fig. 3 and some of the slides 144 rotate the type gear wheels 380 to normal position.

The construction of the type wheel carrying frame 382, its mounting means, and the means for effecting the reciprocation of said frame in the manner just described is best shown in Figs. 24, 25 and 26. At the left end of frame 382 there is provided an integral ear 387 carrying a pair of rollers 388 cooperating with a fixed guide rail 389. The right hand end of the frame casting 382 has an integral portion 390 having integral webs 391, which encircle a fixed guide rod 392. By such mountings the type wheel carrying frame 382 and group of type wheels 380 carried thereby can be shifted from one position to the other. The means for effecting such shifting includes a follower blade 393 carried by frame 382 and cooperating with cam tracks formed in a cylinder 394 rotatably mounted on a shaft 307, to which said driving gear 306 is secured. It will be recalled that, through the punch clutch, gear 306, and therefore cylinder 394, is rotated twelve revolutions.

During the first six rotations of the cylinder 394, the follower blade 393 will cooperate with a cam track designated 396 and at the terminal

portion 397 of said cam track the blade will enter a nearly circular portion 398 which will guide said blade to make an entry at the entry portion 399 of a cam track 400; and in the same manner after the remaining six revolutions a concentric track 401 again positions blade 393 to enter the entry portion of the cam track 396. Said cam tracks are so designed that twelve revolutions of the cylinder 394 will provide the described reciprocating movement to the frame. In Fig. 24 the type wheel carrying frame is shown in the extreme right hand shifted position where the type wheels 380 will be struck by the platen 383 (see Fig. 27a) which occurs at about 90° of the timing diagram in Fig. 18 to effect a print on the tape and inserted card. By cooperation with the track 396, the frame is shifted to the left from such position until at about 175° the printing wheels 380 will be coordinated with platen 384, which will effect the printing on the lower portion of the inserted slip (see Fig. 27b). The continued cooperation of the follower blade 393 with the cam track portion 396 will bring the type wheel carrying frame to the extreme left hand position, so that the actuation of platen 385 against said type wheels at 265° will effect printing on the midportion of the sales slip or issued check (see Fig. 27c). The blade 393 now cooperates with the cam portions 399 and 400 to bring the frame 382 in the position shown in Fig. 3.

Any suitable means may be provided for inking the type wheels and preferably consist of a saturated inking roller 402 (Figs. 3 and 25) which is urged by a lobster spring 403, so that its inked periphery will cooperate with the type on the type wheels 380.

The platen 383 for printing upon the tape as well as on the inserted card, if it is inserted to overlap the tape, is best shown in Fig. 11 and comprises a rubber impression block carried by a pair of arms 410 which are sleeved together and are loosely mounted on a rod 411. A bail rod 412 is carried by arms 413 which are secured to the rod 411 and said platen and arms 413 are interconnected by a spring 414. By means to be subsequently described a cam action is effected on the rod 412, so as to rock both the bail rod frame and the platen counterclockwise against the action of a spring 415. Thereafter, the cam passes by the rod 412 and spring 415 is now effective to rock the platen 383 upwardly by means of the elevated bail rod 412, thus effecting the printing impression upon the inserted card and also the tape.

For actuating the platens, there is pivotally mounted on the rod 381 a pair of arms 420, 421 (Fig. 24) in scissors formation and interconnected by a spring 423. The arm 420 has an extension 424 engaging a fixed stud 425 to prevent clockwise movement of arm 420. The arm 421 has an extension 426 engaging a fixed stud 427 to prevent counterclockwise movement.

As the frame 382 moves to the right, a cam edge 428 of arm 420 engages the rod 412 to cam the platen operating frame downwardly, since arm 420 cannot rock clockwise by such engagement. Cam edge 428 finally moves beyond rod 412 as shown in Fig. 27a to release the platen which is then operated by spring 415 to take an impression. When frame 382 moves to the left, arm 420 trips or rocks idly counterclockwise until it passes by rod 412.

A similar cam operation is effected upon the platen 384 by the cam arm 421 as the type wheel carrier frame moves to the left as shown in Fig.

27b, and then also by the same cam arm 421 on platen 385 when the type wheel carrier frame is at the extreme left hand position as shown in Fig. 27c.

Referring to Figs. 32 and 34 for reciprocating the bail rod frame associated with platen 384, there is secured to the rock shaft 411 an arm 416a carrying a roller 417 operated by lower cam edge of arm 421, and the same cam edge of arm 421 engages a roller 418 carried by an arm 419 having a pin and slot connection 429 to an arm 416b secured to the shaft 411 of the bail rod frame associated with platen 385.

When a cam arm 420, 421 is not to cam a platen, it merely rocks idly as before stated.

It should also be mentioned that after the punching operation the punch operating frame is at the left hand or forward position at the end of the machine cycle. When the frame 382 moves to the right, the frame part 381 (Figs. 3 and 25) will strike the upper portion of the punch operating frame at about 30° of the next cycle (see Fig. 18) and restore said frame at 90° ready for moving step by step for the next punching operation.

Printing and punching on paper tape

From Fig. 3 it will be observed that the tape is printed at the left by the platen 383 and punched at the right, so that successive recorded entries are each printed over the corresponding data punching, as shown in Fig. 15. To space successive recorded entries, the following means is employed.

33 The tape to be recorded on is preferably in overlapping fan-fold fashion in a magazine 430 (Fig. 3) and the tape passes over a loosely mounted sprocket wheel 431, thence between the punching mechanism with the tape beneath the punches 179 and over the platen 383, and thence passing over sprocket wheels 432 to a storage magazine 434. Sprocket wheels 431, 432 engage the marginal perforations of the tape. The shaft 433 on which sprocket wheels 432 are secured is driven by the following means.

Referring to Figs. 4 and 9, secured to the drive shaft 271 is a gear 435 which drives a gear 436 through an idler gear 437. A mutilated gear 438 secured to gear 436 meshes with the teeth of a Geneva type gear 439 secured to the shaft 433. The gear ratio and mutilated gear drive is such that the tape feed begins at 270° (see Fig. 18) and terminates at the end of the cycle. In this manner the punched and printed tape is fed to space successive recorded sections.

It will be recalled that pin 60 is carried by gear 438 which effects the operation of means to release certain banks of keys, as previously described.

Printing and punching of machine number

It is desirable to print upon the issued check, inserted slip tape, and inserted card the number of the machine involved in the transaction and to also punch a number representation on the tape and inserted card, so that the sales entered in each machine may be segregated for statistical purposes.

To this end there is provided three slides 445 similar to the punch slides 144 and having teeth at the forward portion to rotate three type wheels 446 (see Fig. 28). The slides 445 are also provided with punch selecting interposers similar to that described and shown in Fig. 3 for punching on the tape and inserted card. Slides 445 are

differentially set in the machine to represent the desired number by having access within the machine for positioning the slides. The adjusted position of each slide is held by a spring urged locking pawl 447 having a finger piece 448 for freeing said slides for differential movement.

Printing number representing number of month and day

It is desirable to print on the issued check, inserted sales slip, and also the inserted record card the number of the month and the day thereof. To effect this, there is provided four slides 450 (Fig. 29) similar to the punch slides 144 except that they do not carry punch interposers. The forward teeth of said slides mesh with four type wheels 451 (see Fig. 26) and such type wheels are set to represent calendar data to be printed on the different record materials. To effect the setting of the slides to represent the dates as they change, there is provided four knurled wheels 452 (see Figs. 1 and 10) which have a shaft and sleeve connection to four gears 453 which are in mesh with the four settable slides 450. The desired setting of the slides is retained by spring-pressed aligning pawls 454.

Serial numbering punching

It is desirable to serially number record materials by printing the same serial number on the issued check, the inserted slip, the record card and also punch a serial number representation, both upon the tape and inserted card as is shown in Figs. 13-16 inclusive. It is desirable to change the serial number representation only upon each operation of the total bar 11 which, it will be recalled, is depressed after a series of item transactions if the sale is a multiple item sale or when the transaction involves but a single item.

To this end there is provided four slides 460 which are similar to punch slides 144 except that they are provided with additional teeth to be described. The forward teeth 461 thereof rotate a group of serial number printing wheels 462 (see Fig. 26) which print the serial numbers on the record material. The slides 460 carry punch interposers so that according to the digit positions of said slides serial numbers will be punched on the tape and inserted record card, according to the code in Fig. 17. In general, if the serial number representation starts at 0, the units slide 460 is moved step by step to represent digit positions 1 to 9. Each step of operation is effected only on a total operation when motor bar 11 is depressed. When the units order slide passes from 9 to 0, the tens order slide is given one step of movement and the units order slide is returned to its starting position. The arrangement for effecting this operation is shown in Fig. 30 and is described as follows.

It will be recalled that the differential mechanism related to the item and total bars is given a one-step movement when item motor bar 10 is depressed and four steps of movement when the total motor bar 11 is depressed. The aforesaid mechanism causes the rocking of one of the crossover shafts, the particular one being designated 146C in Fig. 30, and this shaft therefore rocks either one step or four steps. Secured to said shaft 146C is a gear 463 meshing with a mutilated gear 464 to provide a Geneva gear drive by meshing with teeth 465 of a segment 466 loosely mounted on shaft 142. A depending arm 467 of said segment pivotally carries by a rod a slide actuating frame 469 having four teeth 470

of differing lengths. Each tooth 470 cooperates with ratchet teeth 471 on the related slide 460. A spring 472 which is wound around the pivot shaft 468 urges the slide actuating frame 469 so that the teeth 470 will engage the teeth 471 of the slides but such movement is normally prevented by means of a cam 473 secured to shaft 142 and engaging a stud 474 carried by an extension of said frame 469. It will be recalled that shaft 142 is the shaft which is rocked to effect the reciprocation of the bail plate 131 (see Fig. 3) and shaft 142 rocks first counterclockwise disengaging cam 473 from the stud 474 and allow the frame 469 to move clockwise to actuating position, and said cam 473 is reversely rocked clockwise to the Fig. 30 position to rock and hold frame 469 in the position shown.

The one-step counterclockwise movement given to the Geneva gear 464 by the gear 463 in item operation is insufficient to rock segment 465 at all, and therefore cam 473 merely allows the frame 469 to rock down and then up to normal. However, for total operation the Geneva gear 464 will rock the segment 465 sufficiently to move frame 469 one step forwardly to engage a tooth 470 with a tooth 471. When cam 473 has allowed said frame to move down to actuating position, said frame is moved rearwardly and the slide 460 is moved one step. Assuming that the units order slide 460 is at the 0 position, a tooth 470 will then engage the rearmost tooth 471 and move said slide 460 one step to the rear to represent the digit 1. By the repeated operation when the next total operation is effected, the digit slide 460 will be moved to the 2-digit representing position, etc.

It is, of course, necessary that the next higher order slide 460 be moved a unit when the lower adjacent order slide 460 goes from 9-0 digit position, and this is the reason for the varying lengths of the pawls 470. At such digit position 9-0, the related tooth 470 will drop in a deep notch 475, allowing the tooth 470 related to the slide of the next denominational order to engage a tooth 471 of said slide so that, when said actuating frame 469 is moved rearwardly, it will move the slide 460 of next higher order one step to increase its digit position by one. This is a well known construction of effecting transfers and has been employed in transfer devices for serial number representing wheels. At the rearward position of the slides 460, there is provided a spring-urged holding pawl 476 cooperating with ratchet teeth 477 of the related slide. When a slide moves from 9-0 digit position, it should, of course, be returned forwardly to normal position. As each slide 460 is moved rearwardly step by step, its coaction with a roller 478 on a plate 479 will rock said plate counterclockwise to extend a spring 480, said spring, therefore, normally urging the related slide 460 forwardly, but is frustrated by holding pawl 476. As the slide 460 moves from 9-0 digit position, a roller 481 carried by said plate 479 will hit an extension 481 of said pawl 476 and rock the pawl counterclockwise, freeing it from cooperation with the last notch 477 of the slide. Spring 480 is now effective to return the slide to its normal position, and at this time the coacting frame 469 has been rocked to its normal position with teeth 470 out of cooperation with teeth 471 on the slides 460. To prevent any interference in the return forward movement of each slide 460 by the pawl 476, said pawl has an extension 482 and in the last described rocked position of the pawl 476

said extension will overlie shouldered extension 483 of a spring-pressed latch pawl 484. Said latch pawl 476 is free to be rocked to latch the pawl 484 when a stud 485 on each slide moves rearwardly away from coaction with a tail 486 of the related latch pawl 484. The stud 485 is also effective to rock latch pawl 484 to unlatch it from the holding pawl 476 when the slide 460 returns to its normal starting position.

No check and slip printing upon item recording for multiple items

When recording a series of multiple items in the machine, it is desirable that when item motor bar 11 is operated neither platen 384, 385 be operated, and are operated to effect recording only when total motor bar 11 is operated.

As best shown in Figs. 32, 33, 34, the printing mechanism for the check and inserted slip is mainly carried by two side frames 500, 501 cross connected by suitable cross members. Slidably mounted on studs 503 (Fig. 32) on the side frame 500 is a cam control plate 502. One cam slot comprising cam portions 504a, 504b, 504c coacts with a stud 505 carried by an arm 506 secured to a shaft 507, said shaft 507 carrying a pair of hooked locking members 508, which hook over the platen 384. Another cam slot comprising cam portion 509a, 509b, 509c coacts with a roller 510 carried by an arm 511 secured to a rod 512. Said rod carries a pair of hooked members 513 which hook over platen 385.

The cam plate is urged to the right, as shown in Fig. 32, by a spring 515 and to prevent this for item recording operations the cam plate 502 carries a stud engaged by an arm 517 secured to a shaft 518.

In Fig. 2 one of the shafts 106 carries a pinion meshing with a segment 519 and said shaft and pinion are associated with the differential mechanism of the item motor bar 10 and total motor bar bank, and therefore is rocked one or four steps of movement. Segment 519 carries at its lower extension 520 a stud 521 engaging a slot in a forked member 522 secured to rock shaft 518. In the one step rocking movement of segment 519, when item motor bar 10 is depressed, stud 521 merely coacts with an arcuate edge in the slot which is so designed that the slight movement given to segment 519 will retain arm 522 in the position shown in Figs. 2 and 32 so that cam plate 502 will stay in the position shown in Fig. 32 to keep platens 384, 385 locked by the hooked members 508, 513.

Check issuing and recording

In the absence of printing upon an inserted sales slip, a printed check conforming to Fig. 13 is issued upon depression of total motor bar 11.

This is effected by operating platen 385 which is unlocked by allowing cam plate 502 to go to its extreme right hand position in which position low cam portion 504c will have rocked shaft 507 to keep platen 384 locked by hooked members 508. Cam portion 509c which is a high portion will have rocked arm 511 and shaft 512 to move hooked members 513 to unlocking position.

Such movement of cam plate 502 is permitted by the four-step rocking movement of segment 519 which moves stud 521 to such position that member 522 and shaft 518 are rocked to such a position that arm 517 secured to rock shaft

518 rocks counterclockwise to allow the extreme right hand movement of control plate 502 by spring 515.

The check to be printed upon is drawn from a roll of paper 525 (Fig. 3), the paper 526 extending upwardly, then passing over a horizontal guide plate 527 (Figs. 33 and 34), thence downwardly to pass between feeding rollers 528, 529. Said plate 527 is apertured as shown in Fig. 34 to allow the platens 385 to strike the check paper against the inked type wheels 380 to effect the imprint.

Normally, there is a separation between the printing roller 528 and an electro roller 529 as shown in Fig. 33 for the free insertion of paper, and roller 528 is driven by a one-way clutch drive now to be described. Coacting with electro plate roller 529 is a spring-pressed inking roller 530, and rollers 528 and 529 are intergeared in the conventional manner.

Loosely mounted on a rod 535 is a segment 536 meshing with a pinion 537, and intermediate said pinion and shaft 538 to which roller 528 is secured is a one-way one-tooth clutch 539 (Fig. 34).

Loose on rod 535 is an operating member 540 forked at the end to provide a slot 541 into which enters a stud 542 (see Fig. 24), carried by the type wheel carrying frame 382. Pivoted on the segment 536 on a stud 543 is a hook-shaped latch member 544 which is adapted to hook over a stud 545 carried by the operating arm 540. A pin 546 carried by latch member 544 engages an upper straight edge of an extension 547 of control plate 502 in the normal position of control plate 502 (Fig. 32), and its intermediate position, but in the extreme right hand position the pin 546 will coat with a depressed part 549 of extension 547 to allow latch member 544 to rock counterclockwise to latch or hook over pin 545, thus connecting segment 536 and operating member 540 together.

Thus, segment 536 will be rocked upwardly as the type wheel frame is shifted to the extreme left hand position, but roller 528 will not turn due to the idle one-way clutch drive by clutch 539. Hence, paper strip 526 will not be fed to allow at this time printing on the check.

As the segment 536 is reversely rocked, the clutch drive 539 will feed the check paper between 270°-300° (see Fig. 18) and thus feed the check paper to the front of the machine in a check receiving slot 550 (Fig. 33).

The printed part of the check is cut off after feeding, starting at 305° (see Fig. 18) by the following means.

The printed check passes between a fixed knife 551 (Fig. 33) and a slid able guillotine knife 552 carried by a pair of arms 553 secured to a rock shaft 554.

To shaft 554 (see Fig. 2) there is secured a rock arm 555 having a pin and slot connection to an extension 556 of a cam follower arm 557 associated with complementary cams 558 secured to cam drive shaft 271. Rocking of the lower movable knife 552 will thus sever the printed part of the check paper from the remaining check paper.

Printing on sales slip

Printing on the sales slip is effected in two places by platens 384, 385 which are both conditioned to be operated when control plate 502 is in its intermediate position which enables high cam portions 509b, 504b to keep all hooked members 508, 513 to platen unlocking position.

Prior to an operation of total motor bar 11, a sales slip (Fig. 14) is placed on a sales slip carriage 565 (Figs. 37 and 38) which is pulled outwardly through a slot in front of the machine. Placing the sales slip on the carriage 565 and pushing it inwardly conditions the printing mechanism for printing on the inserted sales slip.

The carriage 565 comprises a base plate 566 apertured so that platens 384, 385 may project through. To the top of base plate 566 there are secured guide bars 567, 568 coacting with the horizontal edges of the sales slip. A lug 569 comprises the rear stop for the sales slip. At the forward portion of plate 566 there is attached a pair of support members 570 carrying a pivot rod 571 for a spring-operated clamp plate 572 under which the forward end of the sales slip is inserted to be clamped thereby. Depending lug 573 is a convenient fingerpiece for moving the sales slip carriage.

The sales slip carriage 565 is slidably mounted in channel slots in the top of side frames 500, 501, in any suitable manner.

Coacting with a notched bar 574 (Fig. 38) under the base plate 566 is a spring-pressed pawl 575 which coacts with an aligning pawl notch 576 when the sales slip carriage is inward and a stop notch 577, when the sales slip carriage is completely outward (see Fig. 38).

When the sales slip carriage is completely inward, a shoulder 578 coacts with a blade of contacts 579 to close the latter. These contacts will be explained in connection with the circuit diagram.

Projecting in a slot 585 (Fig. 37) is a sales slip sensing lever 586. When a sales slip is on the carriage and clamped down, the slip itself will rock lever 586. Lever 586 has a sleeve connection 587 (Fig. 34) to an arm 588 (Fig. 32) which is connected by a link 589 to an arm 590. The arm 590 is pivoted on a stud 591 and drawn by a spring 592, so that in the absence of a sales slip a lug 593 on arm 590 will be out of the path of a shoulder 594 of the extension 547 of cam plate 502. When a sales slip is on the carriage and has rocked lever 586, the arm 590 will be elevated and lug 593 is now in the path of shoulder 594. This will cause cam plate 502 to be moved to the intermediate position, so that both platens 384, 385 will be unlocked to be operated to print on the sales slip in two places (see Fig. 14).

Perforated record card support carriage

Projecting from the left side of the machine is a card support plate 600 (Figs. 1 and 35) over which a card to be punched is placed and pushed in a slot in the cabinet of the machine. A pin 601 coacts with the well known diagonally cut corner of the card to insure insertion of the card in proper position. Upstanding guide portions 602, 603 guide the inserted card and, when completely inward, the inside shorter marginal edge of the card abuts the pin 228 (see Fig. 11). The pin 228 slides along this card edge, since the card is fixed during the punching operation.

The card support plate has ears 604, 605 secured to an intermediate frame 606 to hold the plate in position.

Means for unlocking total motor bar 11

Referring to Fig. 4, it will be recalled that total motor bar 11 is normally locked unless solenoid 248 is energized. The energizing circuit (Fig. 31) is controlled by the aforementioned contacts

88, 91, 98, 97 closed when clerks and department numbers are set up as previously described, and contacts 579 closed when the sales slip carriage is inwardly, whether a slip is on the carriage or not. In addition, the solenoid 248 is not energized unless contacts 610 are closed, which is effected when a key in the transaction bank is depressed.

Referring to Figs. 4 and 8, overlying the arm 36 associated with the transaction key bank is a pin 611 carried by a double arm 612 (see Figs. 4, 8 and 31) loosely pivoted on rod 50, which arm causes the closure of contacts 610 when said arm is rocked by the rocking of arm 36 caused by the depression of a key in the transaction key bank.

When all contacts are closed, the circuit to energize solenoid 248 is completed, and total motor bar 11 is now unlocked for depression.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a record punching machine, the combination of a plurality of members, each differentially adjustable 1-9 units and carrying a plurality of punch-actuating interposers, a punch hammer carrying a series of punch engaging projections cooperating with said punch-actuating interposers in various combinations according to the adjustment of said member to effect punching of holes in combinational arrangement for a single character representing unit, a punch pin, means for shifting said punch pin step by step for coordination with said punch-actuating interposers and successive index point positions of a stationary record to be punched, and means for reciprocating said punch hammer once for each of the successive positions of said punch pin to effect an operation of said punch pin by a punch operating projection through a punch-actuating interposer.

2. In a record punching machine, the combination of a member differentially adjustable and carrying a series of punch-actuating interposers, a punch hammer carrying variously disposed punch operating projections engaging with said punch-actuating interposers in various combinations according to the adjustment of said member to effect punching of holes in combinational arrangement for a single character representing unit, means for holding and locating a record to be punched having rows of index point positions, a punch pin, means for shifting said punch pin step by step with respect to said record and for coordination successively with the rows of index point positions, and means for reciprocating said punch hammer once for each of the successive positions of said punch pin to cause a punch operating projection through a punch-actuating interposer to operate said punch pin.

3. In a record punching machine, the combination of a member differentially adjustable to a plurality of different positions, said member carrying variously arranged punch-actuating interposers, a punch hammer carrying variously disposed punch operating projections engaging

with said punch-actuating interposers in various combinations according to the position of said member to effect punching of holes in combinational arrangement for a single character representing unit, a punch pin, means for holding a record to be punched, means comprising a reciprocable carriage for shifting said punch pin step by step for coordination with successive index point positions of said record to be punched, means for reciprocating said punch hammer once for each of the successive positions of said punch pin to effect a punching operation of said punch pin through each punch-actuating interposer correlated with a punch operating projection, and means cooperating with the punch pin movable with each operation of the punch pin, to punch a hole, the return idle operations of said means positively withdrawing the punch pin out from the punched hole.

4. In a record punching machine, the combination or an adjustable member carrying a series of punch-actuating interposers, a successive reciprocable punch hammer having variously disposed punch operating projections, said projections and punch-actuating interposers being operatively engaged in different combinations to effect combinational hole punching for a single character representing unit according to the decimal adjustment of said member, a punch pin, and means to operatively associate said punch pin with said punch-actuating interposers in succession.

5. In a record punching machine, the combination of a decimal adjustable member carrying punch-actuating interposers, a successive reciprocable punch hammer having variously disposed punch operating projections, said projections and punch-actuating interposers being operatively engaged in different combinations to effect combinational hole punching for a single character representing unit according to the decimal adjustment of said member, a single punch pin, means to operatively associate said punch-actuating single punch pin with said interposers in succession, and means to operate said punch hammer and said last named means in timed operations to cause a projection on said hammer to effect the operation of said punch pin through a punch-actuating interposer.

6. In a record punching machine, the combination of means to position a plurality of punch-actuating interposers to different positions, a successive reciprocable punch hammer having variously disposed punch projections, said projections and punch-actuating interposers being operatively engaged in different combinations according to the adjustment of said punch-actuating interposers to effect combinational hole punching for a single character representing unit according to the decimal adjustment of said member, a punch-actuating pin underlying said punch interposers, and means to shift said punch pin beneath said punch-actuating interposers in succession and to effect an operation of said punch hammer to effect the operation of said punch pin through each punch-actuating interposer which is beneath a projection.

7. In a card punching machine, a consecutive number counter comprising a plurality of adjustable elements of successive denominational order, means to adjust said elements to represent consecutive serial numbers, a plurality of punch interposers carried by each of said elements, a punch operating hammer comprising punch operating projections variously disposed and coordi-

nated with said punch interposers in different combinations to effect combinational hole punching to represent on a series of records consecutive serial numbers, and punching means for each order selected for actuation by each of the interposers which are coordinated with said punch operating projections.

8. In a record card perforating machine, the combination of a serial number representing device comprising a plurality of denominational slides, adjusting means cooperating with said slides to advance one or more of said slides to represent consecutive serial numbers, said adjusting means including means controlled by each lower denominational slide to advance the next higher order slide a unit when said lower slide goes from 9-0, means for automatically returning each lower order slide to a zero normal position following the adjustment of said slide from 9-0, a plurality of punch interposers carried by each of said slides, a punch operating hammer carrying variously disposed punch operating projections which are operatively associated with said punch interposers in various combinations to effect combinational hole punching, and punching means for each order selected for actuation by each of the interposers which are coordinated with said punch operating projections.

9. In a record card perforating machine wherein two different types of operations are performed, the combination of a serial number counting device comprising a plurality of denominational members, adjusting means cooperating with said members to advance one or more of said members to represent consecutive serial numbers, said adjusting means including means controlled by each lower denominational member to advance the next higher order member a unit when said lower order member goes from 9-0, operating means operable different extents for the two different types of operation and for causing the operation of said adjusting means by the extent of operation in one of the above types of operation, means for automatically returning each lower order member to zero normal position following the advance of said member from 9-0, a plurality of punch interposers carried by each of said members, a punch operating hammer carrying variously disposed punch operating projections which are operatively associated with said punch interposers in various combinations to effect combinational hole punching, and punching means for each order selected for actuation by each of the interposers which are coordinated with said punch operating projections.

10. In a record card perforating machine, the combination of a serial number counting device comprising a plurality of denominational slides having a series of notches and a deeper notch, adjusting means cooperating with notches in said slides to advance one or more of said slides to represent consecutive serial numbers, said adjusting means including a member having a plurality of fingers of different lengths cooperating with said series of notches and each movable in said deeper notch of a related lower order denominational slide to advance the next higher order slide a unit when said lower slide goes from 9-0, means for retaining each slide in advanced position, means for automatically disabling the retaining means of each lower order slide to enable its return to zero normal position following the advance of said slide from 9-0, a plurality of punch interposers carried by each of said slides,

a punch operating hammer carrying variously disposed punch operating projections which are operatively associated with said punch interposers in various combinations to effect combinational hole punching, and punching means for each order selected for actuation by each of the interposers which are coordinated with said punch operating projections.

11. In a record card perforating machine, the combination of a serial number counting device comprising a plurality of denominational slides, each having a series of notches and a deeper notch, adjusting means comprising fingers of different lengths cooperating with the series of notches in said slides to advance one or more of said slides to represent consecutive serial numbers, a finger of said lower order denominational slide cooperating with said deeper notch to cause a finger related to the next higher order slide to advance said higher order slide a unit when said lower order slide goes from 9-0, means for automatically retaining each slide in advanced position, spring means to return each slide to zero normal position, means for disabling the retaining means of each lower slide and causing said spring means to return each lower order slide to zero normal position following the advance of said slide from 9-0, means for rendering the retaining means of each slide effective following the arrival of said slides to zero normal position, a plurality of punch interposers carried by each of said slides, a punch operating hammer carrying variously disposed punch operating projections which are operatively associated with said punch interposers in various combinations to effect combinational hole punching, and punching means for each order selected for actuation by each of the interposers which are coordinated with said punch operating projections.

12. In a punching machine, punching means for making records, said devices including a plurality of differentially movable elements, means

for controlling said last named means comprising a plurality of members, each having associated therewith a plurality of stops of differential lengths to control the differential movement of said elements, and means for selecting which of the aforesaid members are to cooperate with the aforesaid differentially movable element comprising a manually rotatable drum by which said members are carried and selectively positioned.

13. In a punching machine, a plurality of differentially movable elements, a plurality of punch interposers carried thereby, a punch operating hammer carrying variously arranged punch operating projections and coordinated with said interposers in various combinations to effect combinational hole punching, punching means for each movable element selected for actuation by each of the interposers which are coordinated with said punch operating projections, means

for controlling the differential movement of said elements comprising a plurality of members, each having associated therewith a plurality of stops of differential lengths to control the differential movement of said elements, and means for selectively positioning said members to control positions comprising a single member adjustable to different positions and carrying said members.

Certificate of Correction

Patent No. 2,490,373

December 6, 1949

RALPH E. PAGE ET AL.

It is hereby certified that errors appear in the printed specification of the above numbered patent requiring correction as follows:

Column 26, lines 36 and 37, for "engaging projections cooperating" read *operating projections engaging*; column 27, line 17, for the word "operations" read *operation*; and that the said Letters Patent should be read with these corrections therein that the same may conform to the record of the case in the Patent Office.

Signed and sealed this 11th day of April, A. D. 1950.
